PRODUCTION OF HYDROCARBONS

Fritz Winkler and Hans Haeuber, Ludwigshafen-on-the-Rhine, Germany

No Drawing. Application February 18, 1931,
Serial No. 516,829, and in Germany February
20, 1930

4 Claims. (Cl. 260—170)

This invention relates to improvements in the manufacture and production of hydrocarbons from gaseous or vaporous hydrocarbons of the methane series.

8 Unsaturated hydrocarbons, such as ethylene, propylene and the like, may be readily converted into valuable liquid hydrocarbons, such as benzene and benzine, without any injurious deposition of carbon by employing as catalysts heavy metals of group 1 of the periodic system, namely gold, silver or copper or alloys of gold, silver or copper, as for example brass, (bronze, manganese-copper or alloys of gold or silver with copper, or a coherent heat-resistant metal such as iron, copper or alloys such as V2A steel or the like which has been coated with tin, zinc, lead, aluminium or chromium, especially in such a form that the said catalysts exhibit more or less coherent surfaces. The said metallic coatings are preferably produced by a heat fusion treatment. The surface to be coated is usually immersed in a bath of the molten metal with which it is to be coated or is embedded in metal powder. In this manner between the surfaces of the coating metal and of the metal to be coated an alloy of the two metals is usually formed.

We have now found that the said metallic materials can also be employed in a very advantageous manner for the thermal conversion of gaseous or vaporous hydrocarbons of the methane series and more particularly the homologues of methane into other hydrocarbons, especially into olefines, such as ethylene, propylene, butylene and the like, or into liquid hydrocarbons, especially liquid aromatic hydrocarbons. The said metallic materials are advantageously employed as a constructional material for the apparatus. The said conversion is carried out in the presence of the above mentioned metallic substances with particular advantage when employing free elementary silicon as a catalyst. Commercial silicon may also be employed. So much silicon should always be present in the catalyst that even if some of it enter into combination, free elementary silicon is always present. Metals such as iron or copper may be present in the silicon and it may be employed on non-metallic carriers. If the catalyst is employed in a molded form it is advantageous to prepare it from silicon powder by incorporating therewith non-metallic binding agents such as clay, or other aluminium silicates, or alumina if desired with an addition of metals. The temperatures required for the conversion mainly depend on the nature and the concentration of the hydrocarbons and also on the pressure employed. Propane, for

example, is converted at lower temperatures than methane. A gas containing large amounts of hydrocarbons requires lower temperatures than a gas containing only small amounts thereof. When working under elevated pressures lower 60 temperatures are necessary than at ordinary pressure. Temperatures ranging between 360° and 900° C. have proved satisfactory.

Although generally speaking very high temperatures are necessary for this conversion at which 65 hitherto the danger of deposition of carbon was considerable in many cases, only a very slight deposition of carbon or none at all takes place on the said materials even when working for long periods of time. Moreover, the said materials promote 70 the conversion catalytically to a very great extent.

In many cases it is sufficient to construct the walls of the reaction chamber of the said materials.

As examples of the hydrocarbons which may 75 be converted in accordance with the present invention may be mentioned methane itself or the homologues thereof, such as ethane, propane and butane. Gas mixtures containing these may also be mentioned such as natural gas, waste gases of 80 the destructive hydrogenation of carbonaceous materials such as tars, mineral oils and the like or coke oven gases. Fractions of these gases may also be employed. Furthermore the vapours of benzines, mineral oils, or tar oils of any origin, 85 either alone or mixed with other gases, such as hydrogen, water vapour, methane homologues, olefines, nitrogen or carbon dioxide may be employed.

It is by no means necessary to purify the initial materials from sulphur compounds contained therein, as was necessary when working in the apparatus hitherto employed, but when treating materials containing sulphur, it is necessary to employ as the metal substratum to which the 95 metallic coating is applied a metal or alloy which is not attacked by sulphur, such as V2A steel or other chromium nickel steels.

The nature of the reaction products may be very considerably influenced by the temperature 100 and the duration of the treatment. Thus by employing a relatively high temperature, for example of more than 700° C. and a short period of heating, the gaseous initial hydrocarbons are converted into liquid hydrocarbons under normal conditions of temperature and pressure. These products consist mainly of aromatic and gasoline-like products and they boil mainly below 200° C. They are admirably suited for employment as non-knocking motor fuels or as ad- 110

mixtures to other fuels having a tendency to knock. If medium temperatures as for example temperatures of between 500° and 700° C. and a short period of heating are employed highly unsaturated liquid hydrocarbons are produced from vaporized hydrocarbons. These said liquid products are particularly well suited for employment as initial materials in the production of lubricating oils.

10 The following examples will further illustrate the nature of this invention, but the invention is not restricted to these examples. The percentages are by volume unless otherwise stated.

Example 1

15 10 litres of a gas having the composition 6.16 per cent by volume of butylene, 37.84 per cent by volume of butane, 4.5 per cent by volume of propylene, 39.5 per cent by volume of propane, 20 0.84 per cent by volume of ethylene and 11.16 per cent by volume of ethane are passed per hour at ordinary pressure through a copper tube 18 millimetres in internal diameter and 60 centimetres in length heated to 800° C. 18 litres of 25 a gas containing 4.0 per cent by volume of butylenes and propylenes and 31.0 per cent of ethylene are obtained per hour. Furthermore, 130 cubic centimetres of liquid hydrocarbons, which consist mainly of benzene, are obtained per cubic 30 metre of the gas mixture employed. After working for several days the copper tube is still entirely free from carbon. At higher temperatures the yield of liquid hydrocarbons, especially of benzene, is still higher, and naphthalene and an- 35 thracene are also formed.

Example 2

40 4.8 litres of a gas mixture containing 32.5 per cent of butane, 34 per cent of propane, 9.5 per cent of ethane, 8.4 per cent of higher olefines, 0.8 per cent of ethylene and 14.8 per cent of nitrogen are passed per hour through an internally tinned manganese copper tube 18 millimetres in internal diameter which is heated to 45 700° C. for a length of 60 centimetres. After passing the said mixture through once a mixture of hydrocarbons, containing 60 per cent by volume of olefines which in turn contain 67 per cent of ethylene, is obtained. Deposits of carbon cannot be detected after working for several days.

Example 3

50 7.6 litres of a gas mixture containing about 8 per cent by volume of butane, 35 per cent of propane, 33 per cent of ethane, 4.6 per cent of ethylene, 4.8 per cent of higher olefines and 14.6 per cent of nitrogen are passed per hour through an internally tinned tube of V2A steel 14 millimetres in internal diameter and heated to 800° C. for 60 centimetres of its length. By one passage 55 94 per cent by weight of the hydrocarbons employed are converted, so that (calculated with reference to the initial gas) 24 per cent by weight 60 of ethylene and 25.5 per cent of a liquid product boiling above 40° C. and consisting of aliphatic and aromatic hydrocarbons are obtained. Deposition of carbon does not take place even 65 after working for long periods of time.

Example 4

70 8 litres of a gas mixture containing sulphur compounds and consisting of about 76 per cent by volume of the methane homologues, ethane,

propane and butane, 10 per cent of methane, 4 per cent of hydrogen, 8 to 9 per cent of nitrogen and about 1 to 2 per cent of hydrogen sulphide is passed hourly through a tube having an internal diameter of 20 millimetres and heated over a length of 60 centimetres to a temperature of about 800° C. The said tube is made of V2A steel and is provided internally with a homogeneous coating of lead. It is filled with uniform spheroid lumps of about the size of peas 80 prepared from silicon powder by molding with a binding agent such as clay and heating the mixture at about 1200° C. By a single passage of the gases 90 per cent by weight of the methane homologues contained in the initial gases are 85 converted. Reckoned on the total initial gases, 25 per cent by weight are converted into ethylene and 30 per cent by weight into liquid products boiling above 40° C. and consisting of aliphatic and aromatic hydrocarbons. Carbon is 90 not deposited in the tube.

Example 5

95 2 cubic metres of a gas consisting of 11.5 per cent by weight of olefines, 6.5 per cent by weight 100 of methane, 81.8 per cent by weight of methane homologues and about 0.2 per cent by weight of hydrogen sulphide are passed under a pressure of 50 atmospheres through a tube 5 metres long and 45 millimetres in internal diameter, which is 105 constructed of chromium nickel steel and provided internally with a homogeneous coating of lead. The said tube is filled with spheroid lumps of material consisting to the extent of 90 per cent of elementary silicon. The tube is heated to a 110 temperature of about 550° to 650° C. by means of superheated steam passed around it in the same direction as the direction of flow of the gases.

115 About 67.2 per cent by weight of the methane homologues are converted into liquid products, 30 per cent by weight into methane and 2.5 to 2.8 per cent by weight into gaseous olefines. About 70 per cent by weight of the liquid hydrocarbons obtained boil at a temperature up to 200° C. These 120 consist to the extent of 60 to 70 per cent of aromatic hydrocarbons of low boiling point, such as benzene, toluene and xylene, to the extent of 2 to 5 per cent of styrene and the remainder of aliphatic hydrocarbons of low boiling point. The 125 liquid products of higher boiling point consist almost exclusively of unsaturated hydrocarbons which are very well suited for the production of lubricating oils of high viscosity. The low boiling reaction products are good motor fuels.

130 What we claim is:—

1. A process for the production of olefines, which comprises passing a gas comprising butane, propane and ethane through an internally tinned manganese-copper tube, which is heated to about 135 700° C.

2. A process for the conversion of an impure hydrocarbon of the methane series containing sulphur into more valuable hydrocarbons, which comprises treating said hydrocarbon of the methane series at a temperature between 360° and 900° C. and in the presence of a heat resistant heavy metal of group 1 of the periodic system and of free elementary silicon.

3. A process for the conversion of an impure hydrocarbon of the methane series containing sulphur into more valuable hydrocarbons, which comprises treating said hydrocarbon of the methane series at a temperature between 360° and 900° C. and in the presence of an alloy of a heat

resistant heavy metal of group 1 of the periodic system and of free elementary silicon.

4. A process for the conversion of an impure hydrocarbon of the methane series containing sulphur into more valuable hydrocarbons, which comprises treating said hydrocarbon of the methane series at a temperature between 360° and

900° C. and in the presence of a heat resistant heavy metal having a coherent surface and coated with a metal from the class consisting of tin, lead, and aluminium and chromium, and of free elementary silicon.
